FRED K. BEZZENBERGER, OF CLEVELAND HEIGHTS, OHIO, ASSIGNOR, BY MESNE ASSIGNMENTS, TO THE FULTON SYLPHON COMPANY, OF KNOXVILLE, TENNESSEE, A CORPORATION OF DELAWARE.

CLOSED METALLIC CORRUGATED WALL AND METHOD OF MAKING SAME.

Application filed August 21, 1924. Serial No. 733,322.

The present invention relating, as indicated, to closed metallic corrugated walls and methods of making same, is more particularly directed to a flexible corrugated wall constituting what is commonly called a metallic bellows and having an end integrally secured thereto, and to a method of forming this end member or closure on the flexible metal wall. One of the principal objects of the invention is the provision of a bellows having an integral end which shall be hermetically and permanently sealed to the tubular bellows and a method of conveniently and economically forming this end on the bellows. To the accomplishment of the foregoing and related ends, said invention, then, consists of the means hereinafter fully described and particularly pointed out in the claims.

20 The annexed drawing and the following description set forth in detail one method and one product exemplifying my invention, such disclosed procedure and product constituting, however, but one of various 25 applications of the principle of my invention.

In said annexed drawing:—

Fig. 1 is a transverse longitudinal section showing a bellows and a die or mold in 30 which the bellows is received ready for the formation on the end of the bellows of a closure member therefor; Fig. 2 is a similar view showing a bellows with an end closure member integrally secured thereto; 35 and Fig. 3 is a view similar to Fig. 1 but showing the uncorrugated end of a tube prior to the corrugating operation in position in a mold for the formation of an end closing member thereon.

40 In Fig. 1 I have shown a corrugated metallic bellows 1 provided with a series of substantially parallel corrugations 2, 3, 4, etc. The bellows, while here represented as being completely formed, may, for the purposes of this description and of this invention, be considered as being either in its finished state or in any intermediate stage of manufacture, that is, with the corrugations either fully or partly formed or as a tube

45 prior to the formation of any corrugations, as shown in Fig. 3. In forming the end closure on the bellows I dispose the end 5 of the bellows 1 within an opening formed in a die 6, after first mounting in this open

end 5 of the tubular wall an end member 7 55 in the form of a disk which is provided with an up-standing flanged button or head 8. The die 6 is provided with portions 9, which engage directly against the side of the end 5 of the wall, and between these portions 9 60 of the die and the outer surface of the corrugation 2 I interpose heat insulating plates 10 of any suitable material, to prevent an undesirable transmission of heat to adjacent corrugations with the resultant reduction 65 of temper therein. The die is also provided with a pouring spout or conduit 11.

When the bellows is thus mounted in place in the die molten metal, either of the same composition as the bellows or of some 70 composition which will cast integrally thereto when it is poured into the die through the opening 11, is allowed to flow around the inner projecting end of the bellows and around the upper surface and projecting head on the closure member 7, and is there allowed to cool, after which the die is removed, leaving the bellows in the form shown in Fig. 2. The end portion 5 of the bellows is then embedded in a cast disk or 75 head 12, which consists of the original closure member 7, the head 8 of which is now firmly embedded in the larger disk which has been cast to the end of the bellows.

If the end of the original tube is to be 80 closed prior to the formation of the corrugations therein then tube 14 is mounted within a die 15, (see Fig. 3), and the closure member 16 is introduced into the open end 85 of the tube, after which metal is cast about the projecting inner end of the tube and against the upper surface of the closure member 16 in the same manner as that already described, with the exception that it is now unnecessary to introduce any protecting elements or means for preventing the transmission of heat along the tube, as is the case when the corrugations are already formed, when the most adjacent corrugations may in some cases be annealed by the 90 temperature to which they are subjected by the closely adjacent presence of the molten metal.

The advantages of the present invention are the economy and convenience of thus 95 closing the ends of the bellows, while at the same time reinforcing these otherwise weak ends by a considerable body of metal which 100

is thus formed integrally therewith and sealed against any possible leakage. It is of course immaterial as to whether the end closures are formed on one or both ends of the bellows, or before or after the corrugating of the bellows. The operation may be performed either in sand molds or in metal molds by die casting, depending upon the material of the tubular wall, the metal to be used in the cast head and the service to which the finished product is to be put, but if the end members are formed by die casting the process can be very rapidly and conveniently carried out by methods well known in this art.

Other modes of applying the principle of my invention may be employed instead of the one explained, change being made in the method or construction, provided the elements stated by any of the following claims or the equivalent of such stated elements be employed, whether produced by my preferred method or by others embodying steps equivalent to those stated in the following claims.

I therefore particularly point out and distinctly claim as my invention:—

1. In a method of forming an integral closure about the end of a metal bellows, the steps which consist in snugly fitting within the projecting end portion of a bellows a metal plate, mounting such end with-

in a mold chamber fitting snugly against the end portion of said tube adjacent a convolution therein, and then pouring molten metal within said chamber about said end while protecting the adjacent convolution of said bellows from the heat of the molten metal.

2. In a method of forming an integral closure for a flexible metallic bellows, the steps which include fitting an end member to the end of the bellows, mounting the bellows end within a mold chamber which embraces the bellows end, and pouring molten metal into said chamber into contact with said end and said end member while protecting the corrugations from the heat of the molten metal.

3. In a method of forming an integral closure for a flexible metallic bellows, the steps which include providing an interlocking end on the bellows, fitting to the end portion of the bellows an end member provided with an interlocking projection, mounting the bellows end within a chamber which fits around the end portion of the bellows, and pouring molten metal into said chamber about said end into interlocking relation with said end member.

Signed by me this 18th day of August, 1924.

FRED K. BEZZENBERGER.
